POCKET CASE FOR MECHANICAL DRAWING INSTRUMENTS

Christine U. Vaughan and Robert E. Bond, Pasadena, and Kenneth A. Milette, La Puente, Calif., assignors to V. & E. Manufacturing Co., Pasadena, Calif., a partnership

Application May 27, 1957, Serial No. 46,375

Term of patent 14 years

(Cl. D87—3)

Fig. 1.

Fig. 2.

Fig. 3.

Fig. 4.

Fig. 1 is a front elevational view of an instrument holder showing our new design;

Fig. 2 is a view taken on the line 2—2 of Fig. 1;

Fig. 3 is a fragmentary side elevational view taken from the lefthand side of Fig. 1; and

Fig. 4 is a fragmentary side elevational view taken from the righthand side of Fig. 1.

The dominant features of our design reside in the portions shown in full lines.

We claim:

The ornamental design for a pocket case for mechanical drawing instruments, as shown and described.
